(57) **CLAIM**

The ornamental design for a battery, as shown and described.

DESCRIPTION

FIG. is a top isometric view of the battery according to an exemplary embodiment;

FIG. 2 is a first side elevation view thereof;

FIG. 3 is a first end elevation view thereof;

FIG. 4 is a second side elevation view thereof;

FIG. 5 is a second end elevation view thereof;

FIG. 6 is a top plan view thereof; and,

FIG. 7 is a bottom plan view thereof.

The broken lines shown in the figures are for illustrative purposes only, and form no part of the claimed design.
